CLAIM

The ornamental design for a portion of a switchboard for electric connections, as shown and described.

DESCRIPTION

FIG. 1 is a perspective view of a portion of a switchboard for electric connections, showing my new design;

FIG. 2 is a front view of the portion of a switchboard for electric connections;

FIG. 3 is a rear view of the portion of a switchboard for electric connections;

FIG. 4 is a right side view of the portion of a switchboard for electric connections;

FIG. 5 is a left side view of the portion of a switchboard for electric connections;

FIG. 6 is a top view of the portion of a switchboard for electric connections; and,

FIG. 7 is a bottom view of the portion of a switchboard for electric connections.

The broken lines showing in the figures are included for the purpose of illustrating portions of the portion of a switchboard for electric connections that forms no part of the claimed design.

1 Claim, 7 Drawing Sheets
